ABSTRACT OF THE DISCLOSURE

Apparatus for automatically reducing the speed of rotation of a motor-driven mandrel in correspondence with the increased diameter of a roll of material wound upon a core carried by the mandrel. A switching device, mechanically-coupled to the mandrel, produces voltage pulses upon rotation of the mandrel. A predetermined number of the voltage pulses are converted into a control voltage which actuates a control device for effecting a predetermined decrease in the speed of the motor.

This invention relates to a machine for winding a plurality of relatively narrow strips of material on individual cores carried by a mandrel and more particularly to apparatus for automatically controlling the mandrel speed in correspondence with the increase in diameter of the wound rolls.

In machines of the class to which this invention is directed, a relatively wide web of material, such as paper or plastic, is slit into a plurality of narrow strips, which strips are then wound into roll form on individual cores mounted on a positively driven shaft, or mandrel. One variable factor which effects the winding of the strips is the normal variation in the thickness, or gauge, of the particular material. This results in the diameter of some wound rolls increasing at a greater rate than others. As the diameter of the wound rolls increases, the rotational speed of the core must decrease since the strips pass to the cores form a pull roll having a constant speed of rotation. Accordingly, it is the practice to mount the cores on the common mandrel in such manner that each core can slip on the mandrel independently of the other core and to an extent corresponding to the tension of the associated strip of material. Generally, this is accomplished by inserting core spacer rings over the mandrel and between each core. Such spacer rings are individually keyed to the mandrel and the assembly of cores and spacer rings is clamped, axially, by suitable loading means carried by the mandrel ends. Thus, the spacer rings are positively driven by the mandrel while each core is free to slip relative to the mandrel as the tension of the associated strip exceeds the frictional restraining force exerted against the core ends by the adjacent spacer rings. This arrangement is commonly referred to in this art as differential winding.

The differential winding arrangement is only a partial solution of the problem of providing uniformly wound rolls of the strip material. As the diameter of the wound rolls increases, there is a corresponding increase in the slippage of the cores, which results in a heating of the spacer rings and cores and mandrel vibrations. The heating of the cores adversely affects certain materials and mandrel vibrations result in wound rolls of poor quality. Further, the heat expansion of the cores and spacer rings results in an increase in the coefficient of friction between these relatively rotatable members, thereby increasing heat generation. The net result is a decrease in the slippage of the cores relative to the mandrel and an increase in the tension of the strips being wound thereon. In the case of very thin material, a tearing through of

2

the strip often occurs. It is, therefore, highly desirable to reduce the speed of the mandrel as the diameters of the wound rolls increase, thereby to maintain a substantially constant slippage between the cores and the mandrel throughout the entire winding operation. This can be done manually, in steps, or automatically by an arrangement which includes a sensing member in riding engagement with the outer convolution of the strip being wound on a selected core. Such prior automatic arrangements generally are critical in operation and may result in an undesirable marking or scoring of the material.

An object of this invention is the provision of an arrangement for automatically controlling the rotational speed of a mandrel in a differential rewinding machine thereby to produce wound rolls of uniform high quality.

An object of this invention is the provision of apparatus for programming the speed of the rewind mandrel of a differential rewinding machine in correspondence with the increased diameter of the wound rolls.

An object of this invention is the provision of a winding machine having a positively driven mandrel carrying a plurality of rewind cores upon which strips of material are to be wound, sensing means producing signals corresponding to the number of rotations of the mandrel, and control means responsive to the signals to effect a change in the mandrel speed.

An object of this invention is the provision of a differential winding machine having a positively driven mandrel carrying a plurality of cores upon which strips of material are to be wound, sensing means coupled to the mandrel and producing a predetermined number of voltage pulses for each revolution of the mandrel, control means controlling the rotational speed of the mandrel, and means responsive to a predetermined number of the voltage pulses and effecting actuation of the control means.

These and other objects and advantages will become apparent from the following detailed description when taken with the accompanying drawings. It will be understood, however, that the drawings are for purposes of illustration and are not to be construed as defining the scope or limits of the invention, reference being had for the latter purpose to the claims appended hereto.

In the drawings wherein like reference characters denote like parts in the several views:

FIGURE 1 is a diagrammatic representation of a differential winding machine incorporating control apparatus in accordance with this invention; and

FIGURES 2 and 3 are schematic circuit diagrams of the apparatus.

Referring now to FIGURE 1, there is shown a mandrel 10 having a longitudinal keyway 11 formed therein, said mandrel carrying a plurality of rewind cores and core spacer rings such as the cores 12, 13 and the spacer rings 14. Each spacer ring is provided with a key disposed in the mandrel keyway. Although not shown in the drawing, the assembly of cores and spacer rings is clamped, axially, by conventional loading means carried by the mandrel, whereby the ends of the spacer rings are pressed against the ends of the cores, the latter generally being made of cardboard.

Before the start of the winding apparatus, the ends of the cut strips 15, 17 of material are secured to the associated cores, as by adhesive tape. These strips have been formed from a wide web of the material by a continuous slitting operation and adjacently-disposed strips are passed around spaced, parallel pull rolls. Specifically, the odd numbered strips pass over the pull roll 18 whereas the even numbered strips pass over the other similar pull roll, not shown, whereby the spacing between the cores 12 and 13 corresponds to the width of the cut strips. The pull rolls are driven at a constant speed from

the main drive shaft of the machine. The mandrel 19, driven by a rewind motor 19, initially is rotated at a predetermined speed to maintain a tension on the strips as they are being wound, thereby providing tightly wound rolls. Thus, each core will slip, relative to the mandrel, in correspondence with the tension of the strip being wound thereon and this tension increases with the diameter of the rewound roll. For example, if the thickness of the strip 15 is slightly greater than that of the strip 17, the diameter of the roll 20 will increase at a greater rate than the roll 21, resulting in an increased slippage of the core 12 as compared to the core 13. Such change in the slippage of the individual cores compensates for the normal thickness variations of the particular material and results in the rolls being wound to a substantially uniform tightness.

It will be apparent that as the diameter of the rewound rolls increases the tension of each strip increases and, therefore, there is a corresponding increase in the slippage of all cores relative to the mandrel. This results in an undesirable heating of the cores and, often, in mandrel vibrations. Consequently, it is highly desirable to reduce the mandrel speed, during the winding operation, preferably in a manner so as to maintain a substantially constant slippage of the cores from the beginning to the end of the rewinding cycles. Further, it is desirable to effect such change in the mandrel speed by means which do not involve physical contact with the material in order to preclude possible marring or scratching thereof. This is accomplished by the apparatus now to be described.

Mechanically-coupled to the mandrel is an electrical contactor 24, which is a single pole, rotary switch having equal on and off time periods as will be described hereinbelow. The switch contacts are connected in a conventional circuit, comprising a capacitor and a source of D.C. voltage, in such manner that the capacitor is rapidly charged when the contacts are open and the capacitor is discharged when the contacts are closed. This produces voltage pulses *a* having a frequency depending upon the speed of rotation of the mandrel. The voltage pulses *a* are applied to a No. 1 flip flop circuit 25 which converts these pulses into square wave voltage pulses *b* having a predetermined constant amplitude and width.

A capacitance decade box 26 comprises three or more multi-contact, rotary switches having indicator knobs 27, 28 and 29 cooperating with scales preferably calibrated in factors relating to material thickness. These knobs are set to the nominal thickness of the particular material to be processed, thereby selectively connecting the internal capacitors to present a predetermined capacitance value to the uni-junction circuit 30. The voltage pulses *b* charge these capacitors and when the capacitors are charged to a predetermined level, the uni-junction circuit fires to produce a voltage pulse *c*. Such voltage pulse is converted to a square wave pulse *d* by the No. 2 flip-flop circuit 31, which pulse is amplified by the amplifier 32 and applied to a stepping motor 33. It may here be pointed out that a control box 34 carries a push-button switch 35 and a signal lamp 36, depression of the switch effecting a resetting of the apparatus and the lamp becoming energized when the resetting function has been completed.

Each amplified voltage pulse applied to the stepping motor 33 causes the output shaft 37 to rotate, say, one-twentieth ($\frac{1}{20}$) of one revolution, such shaft being coupled to a speed reducer 38 having an input to output gear ratio of, say, 18 to 1. The output shaft 39, of this speed reducer, carries a sprocket wheel 40 and is directly coupled to a shaft 41, which shaft is, in turn, coupled to a shaft 42 through an electro-magnetic clutch 43, the latter shaft 42 also carrying a sprocket wheel 44. A second speed reducer 45, having a ratio of, say, 2.25 to 1, has an input shaft 46, carrying the sprocket wheel 47, and an output shaft 48 coupled to a shaft 49 by a second electro-magnetic clutch 50. The shaft 49 carries a

sprocket wheel 51 and is directly coupled to the shaft of a potentiometer 52, which potentiometer may be either a single or a gang type. The aligned sprockets 40 and 47 are coupled by a drive chain 54 and the other sprockets 44 and 51 are coupled by a drive chain 55. Rotation of the arm of the potentiometer 52 changes the speed of the D.C. rewind motor 19 driving the mandrel.

Only one of the electro-magnetic clutches 43 and 50 is energized at any given time. When the clutch 50 is energized, the rotatable arm of the potentiometer 52 is rotated in a direction to insert ohmic resistance into the circuit of the mandrel drive motor 19, thereby reducing the speed thereof. The rate at which this motor slows down depends, essentially, upon the combined ratios of the two speed reducers 38 and 45, since the rotatable arm of the potentiometer now is coupled to the shaft of the stepping motor 33 through both speed reducers. On the other hand, when the clutch 43 is energized, the potentiometer arm is coupled to the shaft of the stepping motor only through the speed reducer 38. Under this condition, the potentiometer arm is rotated in the reverse direction and at an increased speed.

Now, during the winding operation, the clutch 50 is energized and the clutch 43 is deenergized. Thus, the stepping motor 33 drives the potentiometer shaft through both of the speed reducers 38 and 45, and, in the specific example here given, one revolution of the potentiometer shaft requires $18 \times 2.25 = 40.5$ revolutions of the stepping motor shaft. Since one revolution of the stepping motor shaft is effected by the application of 20 pulses to such motor, and assuming a 1 to 1 ratio between the number of pulses *a* (generated by the contactor 24) and the number of pulses *c* (applied to the flip-flop circuit 31), the full range of speed adjustment of the mandrel drive motor 19 will correspond to $40.5 \times 20 = 801$ convolutions of the material wound on the cores. If, now, the decade box 26 is adjusted to provide, say, a 50 to 1 ratio between the pulses *a* and *c* such speed range adjustment of the mandrel drive motor will correspond to 40,050 convolutions of the material on the cores. The actual range of mandrel speed adjustment will depend upon the amount by which the mandrel speed must be reduced to effect a proper winding of rolls to a predetermined maximum diameter and the rate at which such speed adjustment is made will depend upon the thickness of the particular strips being rewound. Generally, a mandrel speed reduction of 30%, from its initial speed at the start of the winding operation, will be satisfactory for coils wound to a diameter of 10 inches on cores having an outside diameter of 3 inches.

To reset the apparatus, after the completion of the winding operation, the push button 35 is depressed. This results in the deenergization of the electro-magnetic clutch 50 and the energization of the clutch 43, thereby coupling the potentiometer arm only to the speed reducer 38. At the same time, the uni-junction circuit 30 is converted into a relaxation oscillator thereby to apply a rapid succession of pulses to the stepping motor for the return of the potentiometer 52 to its initial or starting position at a rapid, predetermined rate.

Reference now is made to FIGURE 2, which is a schematic, partial circuit diagram of the apparatus and including a diagrammatic representation of certain other components for controlling the speed of rotation of the mandrel drive motor. The apparatus is energized upon closure of the line switch 60, thereby applying 115 volts A.C. across the main leads 61 and 62, the lead 61 having a suitable fuse 63 inserted therein. This energizes the transformers 64 and 65. The center-tapped secondary winding of the transformer 64 has connected thereto rectifiers 66 and a conventional filter network, thereby providing 27 volts D.C. across the terminals 67 and 68, such voltage being regulated by a Zener diode 69. The secondary winding of the transformer 65 is connected to the input junctions of a rectifier bridge 70. One output

junction of the bridge is connected to the terminal 71 and the other output junction is connected to the terminal 68. A conventional filter network is connected across the bridge output junctions and the potential across the terminals 68 and 71 is 50 volts D.C.

Closure of the switch 72 connects the operating coil of the power relay 73 across the line leads 61 and 62, said relay having two sets of single-pole, double-throw contacts. When this relay is in the energized condition the lower contacts 74 and 75 are closed, thereby connecting the main drive motor 76, of the machine, across the line leads 61 and 62. It may here be pointed out that this motor furnishes the power required to unwind a web of material from a supply roll, slit such web into a plurality of relatively narrow strips and move such strips to the rewind cores by pull rolls, such as the pull roll 18 shown in FIGURE 1. The upper set of relay contacts, namely, the movable contact 77, the back stationary contact 78 and the front stationary contact 79, are connected into the uni-junction circuit for purposes which will be described hereinbelow with specific reference to FIGURE 3.

The closure of the switch 80 completes the circuit between the mandrel drive motor 19 and a source of 120 volts D.C., such circuit being traced as follows: lead 81, switch 86, potentiometer 52, fixed resistor 83, motor 19 and lead 84. The rotatable arm of the potentiometer is shown in its starting position, in which position there is a minimum total resistance in the motor circuit, whereby the motor runs at a predetermined, maximum speed. It will be understood that the drive shaft of this motor is mechanically coupled to the mandrel 10 (see FIGURE 1) through a suitable gearing system, whereby the initial speed of rotation of the rewind cores is such as to maintain a predetermined amount of tension on the strips of material being wound thereon.

A second power relay 85, having three sets of contacts, normally is in the illustrated, deenergized condition. In such deenergized condition, the electro-magnetic clutch 50 is energized by 27 volts D.C., the circuit being traced as follows: lead 87, the normally-closed relay contacts 88 and 89, lead 90, the normally-closed contacts of a limit switch 91, lead 92, the operating coil of the clutch 50 and the lead 93. The energization of this clutch mechanically couples together the shafts 48 and 49, the shaft 48 being the output shaft of the gear reducer 45 (see FIGURE 1). Thus, the shaft 49 will be rotated in a step-by-step manner in accordance with the application of voltage pulses to the stepping motor, as has been described hereinabove. This results in a rotation of the arm of the potentiometer 52 to insert additional resistance into the circuit of the mandrel drive motor 19. Such additional resistance is inserted into the motor circuit at a predetermined rate in correspondence with the increase in the diameters of the wound rolls carried by the mandrel.

The second set of contacts 95 and 96, of the relay 85, are connected into the uni-junction circuit for purposes which will be described hereinbelow. The third set of relay contacts 97 and 98 constitute lock-in contacts for retaining the relay in the energized condition upon momentary closure of the normally-open contacts of the reset switch 34, as will be described in more detail hereinbelow.

As shown in FIGURE 2, the apparatus is in the starting position, that is, at the start of the winding operation. In such starting position, the lobe on the cam 100, carried by the shaft 49, causes the center contact 101, of a single-pole, double-throw switch 102, to be in engagement with the contact 103. When the contacts 101 and 103 are closed, the signal lamp 36 is energized by the A.C. line voltage, thereby indicating that the apparatus has been fully reset and is in condition for the start of the winding operation. As the winding operation begins, the cam 100 rotates in the indicated direction and the center switch contact 101 becomes disengaged from the contact 103 and engages the contact 104, thereby connecting the line lead

61 to one of the normally-open contacts of the reset switch 34.

As the winding operation progresses, more and more of the potentiometer resistance is inserted into the circuit of the mandrel drive motor 19 causing a corresponding decrease in the motor speed. At the same time, the lobe on the cam 100 rotates toward the limit switch 91. Normally, the cam rotates some 300 degrees, from the illustrated position, from the start to the completion of the winding operation. In the event the winding operation continues beyond a predetermined maximum limit, the cam lobe opens the contacts of the limit switch 91, thereby opening the circuit to the electro-magnetic clutch 50. This disconnects the rotatable arm of the potentiometer from the output shaft 48 (of the gear reducer) so that the arm cannot move beyond the limit of the resistance winding.

Assuming, now, that the winding operation has been completed, the operator opens the motor switches 72 and 80 thereby stopping the machine. To reset the control apparatus, the operator depresses the reset switch 34 to momentarily close the contacts thereof. This results in the energization of the operating coil of the relay 85, the circuit being traced as follows: line lead 61, lead 105, the now-closed contacts 101 and 104 (of the switch 102), lead 106, the closed contacts of the reset switch 34, the operating coil and the lead 107. Since the lower set of relay contacts 97 and 98 are connected in parallel with the contacts of the reset switch, the closure of these relay contacts locks the relay, electrically, in the energized condition. When this relay is in the energized condition, the upper movable contact 89 is engaged with the front stationary contact 108. This results in the deenergization of the electro-magnetic clutch 50 and the energization of the clutch 43. Hence, the shaft 49 (connected to the rotatable arm of the potentiometer) now is disconnected from the shaft 48 and connected to the shaft 41 through the drive chain 55. The shaft 41 is coupled to the output shaft of the speed reducer 38 (see FIGURE 1) which shaft rotates in a direction reverse to that of the output shaft 48 of the other speed reducer 45, upon the application of voltage pulses to the stepping motor. As will be described hereinbelow, the potentiometer arm now is rotated back toward its initial position at a predetermined, increased speed. When the cam 100 returns to its original, starting position, the center contact 101, of the switch 102, becomes disengaged from the contact 104 and engaged with the contact 103. The opening of the contacts 101 and 104 opens the circuit to the operating coil of the relay 85, whereby this relay returns to the deenergized condition. The closure of the contacts 101 and 103 results in the energization of the signal lamp 36 to indicate that the resetting operation has been completed.

It may here be pointed out that the motor control switches 72 and 80, the line switch 60, the reset switch 34 and the signal lamp 36 are located at the operating station of the machine. All other components of the apparatus, with the exception of the rotary contact which is coupled to the rewind mandrel, may be housed within a suitable cabinet attached to the machine or located at a remote position.

Reference now is made to the circuit diagram of FIGURE 3 wherein there is shown the mandrel drive motor 19, the rotational speed of which is controlled by the position of the arm of the potentiometer 52. Through a suitable gearing system, not shown, the motor drives the mandrel 10 at a predetermined, maximum speed at the start of the winding operation. The rotary contactor 24 is mechanically coupled to the mandrel and its contacts open and close, say, three (3) times for each revolution of the mandrel. When the contactor is closed, it discharges the capacitor 110. When the contactor is open, the capacitor is recharged through the resistor 111, which provides a sharp signal pulse to the input circuit of the No. 1 flip-flop circuit 25.

The function of the flip-flop circuit 25 is to provide a

square pulse output signal, having a definite height and width, for each input pulse. Such circuit is a conventional mono-stable (one shot) multi-vibrator comprising two emitter-coupled transistors 112 and 113 biased so that the transistor 113 normally is in the conducting state and the transistor 112 normally is in the non-conducting state. Upon the receipt of an input signal pulse, which occurs when the contactor 24 opens, the transistor 112 is triggered out of its stable state, regeneration occurs, and the astable state will exist for a given time period determined by the values of the resistor 114 and the capacitor 115. After the capacitor 115 has become charged, the transistor 112 returns to its conducting state.

The output voltage pulses produced by the flip-flop circuit 25, having a constant amplitude and width, produce corresponding current pulses in the collector circuit of the transistor 116 (in the uni-junction circuit 30), which pulses charge the capacitors contained in the decade box 26. When the voltage across these capacitors reaches the peak point voltage of the uni-junction transistor 117, this transistor fires and discharges the capacitors. The circuit parameters are such that from 3 to 240 current pulses will be stored by the capacitors before the voltage applied across the uni-junction transistor reaches the peak point voltage, the actual number of such pulses being determined by the total capacitance connected across the leads 118 and 119. Such total capacitance is determined by the setting of the rotary switches 27, 28 and 29 of the decade box 26. The rotary contact of each switch has connected thereto a conventional knob associated with a dial marked in material thickness values or in arbitrary values. In the latter case, the setting of the three switches, for a given material thickness, will be obtained from a reference chart. In any event, the setting of these switches establishes the number of pulses to be stored by the capacitors of the decade box before the uni-junction transistor fires.

Referring specifically to the uni-junction circuit, attention is directed to the contacts 95 and 96 and the contacts 77, 78 and 79 constituting a single-pole, double-throw switch. The contacts 95 and 96 are the similarly-identified, normally-open contacts carried by the power relay 85 shown in FIGURE 2, whereas the contacts 77, 78 and 79 are carried by the relay 73. As has been described hereinabove, during the winding operation, the relay 73 is energized and the relay 85 is deenergized. Thus, during the winding operation, the contacts 95 and 96 are open, whereas the contacts 77 and 79 are closed, and such contact positions are shown in FIGURE 3. Consequently, the emitter of the uni-junction transistor 117 is connected to one side of the capacitors of the decade box by the lead 119. The base of this transistor is connected directly to the voltage terminal 68, to which terminal the other side of the decade box capacitors also are connected by the lead 118. Successive output current pulses of the transistor 116 eventually charge these capacitors to the peak point voltage of the uni-junction transistor, thereby causing such transistor to fire.

When the uni-junction transistor fires, the resulting voltage drop across the input circuit of the transistor 120, of the flip-flop circuit 31, causes this transistor to switch from the non-conducting to the conducting state. This flip-flop circuit is the same as the circuit 25 and produces corresponding output voltage pulses but of predetermined height and width. Such output voltage pulses are applied to the conventional pulse amplifier 32 having an output transformer 121. The voltage pulses generated in the center-tapped secondary winding of the transformer are applied to the stator windings 124 and 125 of the stepping motor 33, which motor is a conventional high torque, uni-directional motor having a low inertia rotor and permanent magnets in the stator. The stator windings are reversed with respect to each other and the rotor 126 is rotated one-twentieth of a revolution in response to each voltage pulse applied to the stator windings by the amplifier 32. The rotor 126 is coupled to the shaft of

the potentiometer 52 through the speed reducers and electro-magnetic clutches, here identified by the numeral 127. The potentiometer arm is coupled to the rotor 126 through both of the speed reducers 38 and 45 (see FIGURE 1), since the clutch 50 is energized and the clutch 43 is deenergized during the winding operation.

As has been described hereinabove, when the winding operation has been completed, the relay 73 (see FIGURE 2) is deenergized upon the opening of the switch 72 by the operator. This results in the opening of the relay contacts 77 and 79 and the closing of the relay contacts 77 and 78. Also, upon momentary closure of the contacts of the reset switch 34 (see FIGURE 2), the relay 85 is energized and locks in electrically, thereby closing its contacts 95 and 96. Under these conditions, that is, during the resetting of the control apparatus, the contacts 95 and 96, of the uni-junction circuit (see FIGURE 3) are closed and the contact 77 is transferred from engagement with the contact 79 to engagement with the contact 78. Now, the emitter of the uni-junction transistor 117 is disconnected from the capacitors in the decade box 26 and connected to the resistor 130, the other end of this resistor being connected to the voltage terminal 67. The uni-junction circuit now operates as a relaxation oscillator at a frequency determined by the values of the resistor 130 and the capacitor 131, which frequency is approximately 33 cycles per second. Square waves, having a corresponding frequency, are now produced in the output circuit of the flip-flop circuit 31, amplified by the amplifier 32 and applied to the stepping motor. At this frequency, the stepping motor runs as a synchronous motor. Also, during the resetting operation, the electro-magnetic clutch 43 is energized (see FIGURE 1) and the clutch 50 is de-energized, whereby the shaft of the potentiometer 52 is coupled to the stepping motor rotor only through the gear reducer 38. Hence, the potentiometer arm is returned rapidly to its initial, or starting position, as determined by the lobe on the cam 100 (see FIGURE 2), which lobe opens the contacts 101 and 104, of the switch 102, and closes the contacts 101 and 103. Opening of the contacts 101 and 104 removes power from the operating coil of the relay 85 resulting in the opening of the relay contacts 95 and 96. The opening of these contacts 95 and 96 (see FIGURE 3) opens the circuit to the emitter of the uni-junction transistor, the circuit ceases to oscillate and the stepping motor is stopped. At the same time, the closure of the contacts 101 and 103, by the cam lobe (see FIGURE 2), results in the energization of the signal lamp 36, indicating the resetting cycle has been completed. Upon removal of the wound rolls, reloading the mandrel 50 with new cores and securing thereto the ends of the cut strips, the machine is in condition for the next winding operation.

In summary, the apparatus for controlling the speed of the mandrel is in condition for proper operation the moment the main drive motor of the machine is energized. When the mandrel drive motor is energized, the rotary contactor, coupled to the mandrel, opens and closes a predetermined number of times during each revolution of the mandrel. This produces signal pulses which are related, frequency-wise, to the speed of rotation of the mandrel. These signal pulses are converted into corresponding square wave pulses having a constant, predetermined height and width. These square wave pulses are converted into corresponding current pulses for charging the capacitors in the decade box. When the voltage level of the charged capacitors equals the peak voltage level of the uni-junction transistor this transistor fires. The number of current pulses which are stored by the decade box capacitors before firing of the uni-junction transistor is determined by the settings of the decade box switch, which settings are made in accordance with the nominal thickness of the particular material being processed. For example, if the material has a thickness of 0.50 mil, the switches would be set so that the uni-junction transistor will fire, say, after 120 charging pulses have been applied

to the capacitors. On the other hand, for a material having a thickness of 16.0 mils, the switch settings would be such as to require only 3 charging pulses to cause firing of the transistor. Upon each firing of the uni-junction transistor, the second flip-flop circuit produces a corresponding output voltage pulse of predetermined height and width. These pulses are amplified and applied to the stepping motor, thereby causing rotation of the arm of the control potentiometer in a step-by-step manner. The added resistance inserted into the circuit of the mandrel drive motor effects a reduction in the speed of rotation of the mandrel. It will be apparent, then, that although the frequency of the initial signal pulses varies with the speed of rotation of the mandrel, the slow-down of the mandrel is effected in a step-by-step manner at a rate which is related to the material thickness, that is, in correspondence with the predetermined increase in the diameters of the rewound rolls.

The winding cycle is completed when the rewound rolls have a desired diameter. The operator then operates the switches to stop the mandrel drive motor and the main motor of the machine. Next, upon the momentary depression of the reset switch, the control circuit is changed so that the uni-junction circuit becomes an oscillator, thereby effecting rapid rotation of the stepping motor. At the same time, the electro-magnetic clutches are actuated to effect a reduction in the gear ratio between the arm of the control potentiometer and the stepping motor and to reverse the direction of rotation of the potentiometer arm. Upon the return of the potentiometer arm to its initial starting position, the signal lamp is energized and the control circuit becomes dormant until the main drive motor and the mandrel drive motor are energized for the next winding operation.

In a duplex machine having two rewind mandrels these mandrels generally are coupled together for rotation by a single mandrel drive motor. Thus, only one control potentiometer is required to effect a slow-down of both mandrels in a predetermined manner and in correspondence with the increased diameters of the rewound rolls.

Having now described the invention, those skilled in this art will be able to make various changes and modifications without thereby departing from the spirit and scope of the invention as recited in the following claims.

I claim:

1. Apparatus for automatically reducing the speed of a motor driven mandrel carrying a core upon which a strip of material is to be wound, which apparatus comprises,

(a) a switch mechanically coupled to the mandrel,
(b) a first means producing first voltage pulses in correspondence with the opening and closing of said switch,

(c) a second means converting the said first voltage pulses into second voltage pulses having a predetermined height and width,

(d) a third means producing a control voltage pulse for a predetermined number of the second voltage pulses,

(e) a stepping motor energized by the control voltage pulse said motor having a shaft which rotates a predetermined angular extent upon each energization of the motor,

(f) a motor control potentiometer having a rotatable arm,

(g) coupling means mechanically coupling the stepping motor shaft to the rotatable arm of the potentiometer for rotation in a predetermined direction, and

(h) means connecting said potentiometer into the circuit of the mandrel-driving motor so as to reduce the speed of such motor upon rotation of the said rotatable arm of the potentiometer.

2. The invention as recited in claim 1, wherein the said coupling means comprises,

(a) a first speed reducer having an input shaft coupled to the stepping motor shaft and an output shaft,

(b) a second speed reducer having an input shaft coupled to the output shaft of the first speed reducer and an output shaft,

(c) a first electro-magnetic clutch adapted when energized to connect the output shaft of the second speed reducer to the rotatable arm of the potentiometer, and

(d) a second electro-magnetic clutch adapted when energized to couple the output shaft of the first speed reducer to the rotatable arm of the potentiometer, the arrangement being such that energization of one or the other of the said clutches produces rotation of the potentiometer arm in one or the other direction.

3. The invention as recited in claim 1, including manually-adjustable means to change the ratio between the number of said second voltage pulses and the control voltage pulse.

4. The invention as recited in claim 3, wherein the said manually-adjustable means includes reference means for setting the manually-adjustable means in accordance with the thickness of the strip of material to be wound on the core.

5. The invention as recited in claim 1, wherein the said first means comprises a first capacitor and a charging circuit; wherein the said second means comprises a flip-flop circuit responsive to each charging cycle of said first capacitor, wherein the said third means comprises a uni-junction transistor having a predetermined peak point voltage; and including a plurality of inter-connectable capacitors, manually-adjustable means to connect said plurality of capacitors to form a resultant capacitor, circuit element for charging the resultant capacitor by the said second voltage pulses, and means connecting said resultant capacitor to said uni-junction transistor to effect firing thereof when the voltage charge on said resultant capacitor reaches the said peak point voltage.

6. The invention as recited in claim 5, including reference means associated with the said manually-adjustable means, said reference means being calibrated in factors related to the thickness of the strip of material to be wound on the core.

7. The invention as recited in claim 1, including manually operable reset means, circuit elements operable upon operation of said reset means to effect a reverse rotation of the potentiometer rotatable arm.

8. In a winding machine of the class having a motor-driven mandrel carrying a plurality of cores upon which

strips of material are to be wound, the combination of,

(a) a set of contacts which open and close in correspondence with the rotation of the mandrel,

(b) a capacitor and a source of charging voltage, said capacitor being charged and discharged in correspondence with the opening and closing of said set of contacts thereby producing signal pulses,

(c) means converting said signal pulses into square wave voltage pulses having a constant amplitude and width,

(d) a plurality of capacitors selectively connectable to form a resultant capacitor,

(e) circuit elements applying the square wave pulses across the said resultant capacitor,

(f) discharging means for discharging the said resultant capacitor when it has been charged to a predetermined voltage level,

(g) means responsive to each discharge of said resultant capacitor to produce control voltage pulses,

(h) means amplifying the control voltage pulses,

(i) a stepping motor energized by the control voltage pulses, said motor having a shaft,

(j) a potentiometer having a rotatable arm,

(k) first and second speed reducers coupled together, the first speed reducer being directly coupled to the stepping motor shaft and the second speed reducer

- being coupled to the rotatable arm of the potentiometer through a first electro-magnetic clutch,
- (l) a second electro-magnetic clutch for coupling the first speed reducer to the rotatable arm of the potentiometer through a direction reversing means,
- (m) means energizing the said first clutch when the mandrel drive motor is energized, whereby the potentiometer arm rotates in one direction,
- (n) circuit elements connecting the potentiometer into the control circuit of the mandrel drive motor to reduce the motor speed as the potentiometer arm is rotated in said one direction,
- (o) manually-operable reset means for de-energizing the mandrel drive motor and the said first clutch, and for simultaneously energizing the said second clutch, and
- (p) means effective upon operation of said reset means to apply a rapid succession of control voltage pulses to the said amplifier thereby resulting in a reverse rotation of the potentiometer arm toward its initial position.
9. The invention as recited in claim 8, including signal means actuated upon the return of the potentiometer arm to its initial position.
10. The invention as recited in claim 9, wherein the said plurality of capacitors are disposed within a case and

5

10

15

20

25

are selectively connectable to form the resultant capacitor by a plurality of rotary switches, and wherein the rotatable member of each switch is alignable with associated reference markings whereby the capacity of the resultant capacitor can be varied in accordance with the nominal thickness of the strips of material to be wound on the cores.

11. The invention as recited in claim 9, including a normally-closed limit switch connected in the circuit of the mandrel drive motor, and means opening said limit switch when the rotatable arm of the potentiometer is rotated beyond a predetermined point in the said one direction.
